(57) **CLAIM**

The ornamental design for a multicooker, as shown and described.

DESCRIPTION

FIG. 1 is a front perspective view of the multicooker in an assembled representation;

FIG. 2 is a bottom perspective view thereof;

FIG. 3 front perspective view of the multicooker in an exploded representation;

FIG. 4 is a front view thereof;

FIG. 5 is a rear view thereof;

FIG. 6 is a left side view thereof;

FIG. 7 is a right side view thereof;

FIG. 8 is a top view thereof; and

FIG. 9 is a bottom view thereof; and,

FIG. 10 is a bottom perspective view thereof.

In some implementations, as shown in FIGS. 1-10 each component of the multicooker includes handles. In some implementations, a front side of a bottom component of the multicooker, as shown in FIGS. 1, 3, 4, and 6 includes a control panel.

The broken lines shown in the figures show features of the multicooker that form no part of the claimed design.
